Letter Patent.

The Sepedale referred to in these Letters Patent and making part of the same containing a description in the body of the said certificate the most honest of his improvement in Tapirs and dies.

The following is a description of Tapirs and dies for cutting reeves of all kinds, with the thread either square round or mixed, either by hand, steam or water power, or power of any other description used to drive machinery, of the Specification of the Tapir. The body or solid part of the Tapir is of uniform original size from end to end. The spiral thread or cutters enter in holes with two deep grooves opposite each other, and running the whole length of the Tapir. The cutters, or spiral threads, beginning at nothing on the plane surface, and gradually rising up to the full size in such manner that each cutter makes a regular cut. The chip being deposited in one of these grooves until it passes off.

And of the Specification of the Dies. The cavity in the Dies, by which the dies is made from, an entire and complete circle, having two wide outer openings across the centre of the Dies, which form the cutters, and also permit the chip to pass off. The reeve in the dies also commences at nothing on a plane surface and gradually increases until the thread acquires the full size.

Attest.
W. C.
